US00D754330S

(12) **United States Design Patent**
Kim et al.

(10) **Patent No.:** **US D754,330 S**
(45) **Date of Patent:** **** Apr. 19, 2016**

(54) **HANDLE FOR A WATER FLOSSER**

(71) Applicant: **WATER PIK, INC.**, Fort Collins, CO (US)

CA 851479 9/1970
DE 1466963 5/1969

(Continued)

(72) Inventors: **Hyunchul Kim**, Chicago, IL (US); **Taiwon Choi**, Glenview, IL (US)

OTHER PUBLICATIONS

(73) Assignee: **WATER PIK, INC.**, Fort Collins, CO (US)

The Right Tool, Electron Fusion Devices, Inc., 2 pages, at least as early as Feb. 1991.

(**) Term: **14 Years**

(Continued)

(21) Appl. No.: **29/508,631**

Primary Examiner — Ian Simmons
Assistant Examiner — Richelle G Shelton

(22) Filed: **Nov. 7, 2014**

(74) *Attorney, Agent, or Firm* — Dorsey & Whitney LLP

Related U.S. Application Data

(63) Continuation of application No. 29/448,929, filed on Mar. 14, 2013, now Pat. No. Des. 717,427.

CLAIM

(51) **LOC (10) Cl.** **24-02**

We claim the ornamental design for a handle for a water flosser, substantially as shown and described.

(52) **U.S. Cl.**

USPC **D24/111**

DESCRIPTION

(58) **Field of Classification Search**

USPC D24/108, 111–113, 133, 152, 176;
D4/101, 104; D8/107

CPC A61C 17/0202; A61C 17/225

See application file for complete search history.

(56) **References Cited**

FIG. 1 is a front, left isometric view of a handle for a water flosser.

U.S. PATENT DOCUMENTS

FIG. 2 is a front elevation view of the handle for a water flosser of FIG. 1.

555,588 A	3/1896	Spencer
1,278,225 A	9/1918	Schamberg
1,464,419 A	8/1923	Gill
1,498,267 A	6/1924	Hachman

2,669,233 A	2/1954	Friend

(Continued)

FIG. 3 is a rear elevation view of the handle for a water flosser of FIG. 1.

FIG. 4 is a left side elevation view of the handle for a water flosser of FIG. 1.

FIG. 5 is a right side elevation view of the handle for a water flosser of FIG. 1.

FIG. 6 is a top plan view of the handle for a water flosser of FIG. 1; and,

FIG. 7 is a bottom plan view of the handle for a water flosser of FIG. 1.

The broken lines, which define the bounds of the claimed design, form no part of the claimed design.

1 Claim, 4 Drawing Sheets
